ANTENNA MAST BASE

Norman Lee, Red Bank, N. J., assignor to the
United States of America, as represented by the
Secretary of War

Application February 11, 1944, Serial No. 521,964

2 Claims. (Cl. 174—153)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to flexible mast bases and more particularly to mast bases of laminated cantilever spring construction.

Current practice in flexible mast base construction has been of the helical coil spring type. This type of mast base has been, of necessity, heavy enough to withstand the bending action to which it is subjected without assuming a set position. Helical spring construction being bulky has considerable capacitance to ground. In some cases this capacity reaches values approximating 20 to 30 micromicrofarads. Capacity of this order has the effect of reducing the field strength in transmission of signals. Helical springs also have inductance and change the electrical adjustments on flexing. This is usually manifested in detuning and noise.

It is well understood in the art that the reduction of capacity between the base of an antenna and the mobile unit supporting it will increase the field strength. In addition to reducing the capacity to ground this invention also provides a decrease in weight on the mast base, a reduction in wind resistance, and the elimination of inductive changes.

It is, therefore, an object of this invention to provide a mast base for mobile use capable of withstanding a deformation of 90 degrees, from a vertical position, without taking a permanent set.

A further object is to provide a mast base of cantilever spring construction.

A still further object is to provide a mast base having good damping characteristics.

A still further object is to provide a mast base that will be very durable and capable of sustaining impact and vibration.

Another object is to provide a mast base having a minimum of capacitance to ground.

A still further object is to provide a mast base that will complement the elastic characteristics of the whip antenna and provide a durable mechanical system.

A further object is to provide a mast base having reduced weight and wind resistance and offering a very small surface as a target to small arms fire.

These and other objects will become apparent from the following description of the illustrative embodiments of the invention shown in the accompanying drawing, the invention residing in

2

the novel method, steps, elements, arrangement of parts in cooperative relation, as hereinafter pointed out in the claims; and exemplified in the practical embodiments of the structure herein described as follows.

Figure 1 is a vertical cross-sectional view of the invention completely assembled and mounted on a support.

Figure 2 is a horizontal cross-sectional view taken along the line 2—2 of Figure 1.

Figure 3 is a vertical cross-sectional fragmentary view of a variation of the fastening means of the invention.

Figure 4 is an elevational view, partly cut-away and sectioned, of a binding post adaptor.

Referring now more particularly to Figures 1 and 2, the assembly illustrated embodies the present invention in a preferred form. A plurality of piano wires 10 or wires of similar elasticity are disposed in juxtaposition to each other, the lower ends of said wires 10 are constrained by suitable means to be described further along. The upper ends of said wires are free to take up their own characteristic length, when bent, by sliding one on the other. In effect, the flexibility of a single strand of piano wire with the strength and restoring force of the bundle is obtained.

The constraining means for the plurality of wires 10 are provided for by a recess 14 into which the constrained end of the plurality of wires 10 are affixed by welding or other suitable means. The recess 14 heretofore mentioned is longitudinally disposed in the upper end of an elongated member 12. As illustrated in Figure 1, member 12 is so machined that it has varying circumferences which provide annular shoulders 15 and 16 and their use will be described hereinafter.

The upper ends of the plurality of wires 10 are placed within a recess 25 which has a sufficient clearance to permit the longitudinal movement of the individual wires 10. The recess 25 is longitudinally disposed in the lower end of an elongated member 23. Longitudinally disposed in the upper portion of the elongated member 23 is a recess 24 within which is placed, a distance therein, a tubular member 26 having circumscribed thereon several rolled threads 27.

An aperture 28, radially disposed in the upper part of the member 23 and in juxtaposition to the rolled threads 27 of the tubular member 26, is provided to permit soldering the said tubular member 26 to the inside surface of the recess 24. Leading from the lower end of the recess 24 is an aperture 23A radially disposed in the elongated member 23 and providing a means of drainage.

Leading to the upper end of the recess 25 is an aperture 29 radially disposed in the member 23 and providing means for lubricating, through this aperture, the plurality of wires 10.

Elongated member 23 is so machined that it provides an annular shoulder 8 the purpose of which will be described hereinafter. Inclosing the plurality of wires 10, and being the means of coupling the upper elongated member 23 to the lower elongated member 12, is a flexible sheath 20. Sheath 20 is attached to the lower portion of the member 23 and the upper portion of the elongated member 12 by soldering or other suitable means. It will be seen now that the shoulders 8 and 16 determine the permissible distance, that the members 23 and 12, can enter the flexible sheath 20 so as to facilitate the soldering operation.

As an additional precaution in maintaining the assembly intact, ferrules 21 and 22 are affixed, at the junction of the flexible sheath 20 and elongated member 23 at one end and the junction of the sheath and elongated member 12, at the lower end by swaging, soldering or other suitable means well known to those skilled in the art.

To eliminate the possibility of moisture entering the recesses 25 and 14, within which the plurality of wires 10 are disposed, a Neoprene or other equally non-hygroscopic covering 30 is provided and is bonded to the outer surface of the assembly comprising a portion of the ferrule 22, all of flexible sheath 20, and a portion of ferrule 21.

Means for fastening the invention to the supporting member 9, and retaining in position thereto the entrance insulators 17 and 18, is an internally threaded recess longitudinally disposed within the lower portion of the elongated member 12 and into which is threaded a bolt 19 and this bolt 19 when drawn up tight into the recess 13 will maintain the entire assembly, Figure 1, in a vertical and rigid position.

A washer 31 of linen and a phenolic condensation product disposed between the shoulder 15 of the elongated member 12 and the upper portion of the insulator 17 provides a means for preventing an undue strain on the insulator 17 when same is drawn tight against the supporting member 9. In a similar manner a washer 32 of linen Bakelite or material of equal composition, is disposed between the washers 19A and the lower portion of the entrance insulator 18. In addition a channel 32A, diametrically disposed in the upper plane surface of the washer 32 and immediately contiguous to the lower end of the entrance insulator 18, provides a means for drainage.

An internally threaded aperture 11 longitudinally disposed in the head of bolt 19 is provided for the insertion of a standard binding post.

Disposed on either side of the supporting member 9 and immediately contiguous to the lower surface of entrance insulator 17 and the upper surface of entrance insulator 18 are washers 17A and 18A which are used to prevent the entrance of moisture at these junctions.

Figure 2 indicates more clearly the disposition of the plurality of wires 10 which constitute a novel feature of this invention together with those components encompassing the said plurality of wires, as described heretofore.

A variation of the fastening means is illustrated in Figure 3. The arrangement of the plurality of wires 10 is similar to that described as Figure 1. In this arrangement the bolt 19 is replaced by member 33 externally threaded at its

upper portion and fastened to the lower entrance insulator 18 by means of a staked nut 37. Longitudinally disposed at the lower end of the member 33, a distance therein, is a recess 38 the purpose of which will be described further along. The member 33 has been machined to provide an annular shoulder 39. A ferrule 37A having an annularly extruded portion 43 at its upper end is slipped over the lowermost portion of the member 33 and placed against the shoulder 39 of the said member 33. The ferrule 37A is composed of a dielectric material and prior to sliding the said ferrule 37A over the aforementioned lower end of the member 33, said lower end is burried and cemented to prevent the said ferrule 37A from slipping off under pressure. An externally threaded annular member 36, burried on its inner surface is slipped over the outer surface of the ferrule 37A and cemented in place. A washer 34 is disposed contiguous to the annular extruded portion 43 and the upper portion of the externally threaded annular member 36, and serves to prevent the entrance of moisture. A washer 41 inhibits the entrance of moisture to the inner cavity of the insulator 17 and is held in place by the shoulder 42 against the said insulator 17.

The aforementioned assembly illustrated in Figure 3 and particularly that portion of the construction at the lower end of member 33, is provided for the attachment of a coaxial cable.

Figure 4 illustrates a binding post adaptor which would permit the substitution, of a single conductor feed (not shown) for a co-axial cable. The lowermost portion 45 has an aperture 46 radially disposed to permit the entrance of the feed wire (not shown) from the transmitting or receiving equipment. Extending downwardly from an internally threaded cup 47 and being a part thereof is an externally threaded member 48 which fits into the member 45. Placing the feed wire (not shown) in the aperture 46 and rotating the member 45 serves to clamp tight the feed wire (not shown). Centrally disposed within the cup 47 and extending upwardly from the bottom thereof is a cylindrical contact 49 of such diameter that it has good contact when inserted in the recess 38, Figure 3.

The ability of ordinary spring wire of small diameter to bend elastically to a comparatively small radius and return to its original shape is well known to those skilled in the art. It is this ability of the small spring wire to resume its original form that is taken advantage of in this present invention together with the cantilever principle of suspension.

In essence, the cantilever spring is composed of a bundle of small diameter spring wires, such as piano wire, all of which are fastened at one end and free to take up their characteristic lengths, when bent, by sliding on one another. In effect, the flexibility of a single strand of piano wire with the strength and restoring force of the entire bundle is obtained. Alternatively, the bundle of wires need not be restrained at either end if they are completely inclosed as illustrated in Figure 1.

Desirable in another respect is the rubbing of the individual wires on one another when bent. This produces friction and tends to stop the mast base from oscillating excessively when released from the deformed condition. The damping effect can be varied by packing the wires more tightly or by the use of greases of different viscosity characteristics.

The construction of the invention is simple. Its dimensions are small enough to reduce the capacity to ground effects considerably, yet, more rugged and much lighter in weight than conventional mobile mast bases. In addition to this feature, by eliminating the helical coil spring, changing inductive values are eliminated.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A mast base, comprising a plurality of piano wires in slideable contact with each other, an elongated metal member of cylindrical configuration, said elongated member having a recess longitudinally disposed at one end therein and an internally threaded recess longitudinally disposed at the opposite end of said elongated member, another elongated metal member of cylindrical configuration having a recess longitudinally disposed at one end therein, and a recess longitudinally disposed at the opposite end thereof, a tubular member disposed within the recess of the aforementioned elongated member and having a rolled thread circumscribing same and disposed a determined distance from the end thereof, means for affixing the aforementioned tubular member to the inner surface of the recess in the elongated member, a bolt having an internally threaded recess longitudinally disposed in the head thereof and means adapted to insulate the entire assembly from a supporting structure.

2. A mast base comprising a plurality of piano

wires, an elongated metal member of cylindrical configuration, said elongated member having a recess longitudinally disposed at one end therein and an internally threaded recess longitudinally disposed at the opposite end of said elongated member, another elongated metal member of cylindrical configuration having a recess longitudinally disposed at one end therein, and a recess longitudinally disposed at the opposite end thereof, a tubular member disposed within the recess of the aforementioned elongated member and having a rolled thread circumscribing same and disposed a determined distance from the end thereof, means for affixing the aforesaid tubular member to the inner surface of the recess in the elongated member, together with a bolt having an internally threaded recess longitudinally disposed in the head thereof.
